pany, New York, N. Y., a corporation of New
Jersey

Application July 20, 1945, Serial No. 606,054

10 Claims. (Cl. 19—69)

1

This invention relates to mechanism adapted to be located at the delivery end of a carding machine and operated to control the weight of the carded web to thereby produce a more uniform sliver.

In the Lewis Patent No. 2,361,217 for apparatus for producing highly uniform sliver, there is disclosed and claimed mechanism for scanning by means of a light a sliver as it passes between successive pairs of drafting rolls. The scanning means serves to control mechanism for increasing and decreasing the speed of one pair of rolls relative to other rolls in accordance with the detected variations in the thickness of the silver to thereby produce a more uniform yarn.

The present invention contemplates mechanism adapted to act upon a carded web as it leaves the carding machine to remove different small amounts of fibers from the web to thereby correct variations in the web weight and produce a more uniform web and sliver. The light scanning mechanism disclosed in the above mentioned patent works well where the mass of fibers to be scanned is thin enough to permit a substantial amount of light to pass therethrough, but is not well adapted for use to scan a thick mass of fibers.

Textile manufacturers are aware of the fact that good carding is the essence and foundation of good yarn, and that no matter how carefully a lap is prepared or the carding machine is operated, the resulting carded web will vary somewhat in weight per unit length. The most pronounced variations usually occur in reappearing waves or cycles. It is the object of the present invention to eliminate these reappearing waves and thereby produce a more uniform carded web or sliver than has been possible heretofore.

To accomplish this it is proposed to operate a carding machine so that it will produce a carded web that is somewhat overweight, and when this web is ready to leave the doffer cylinder trim or otherwise remove enough fibers therefrom to correct variations in the web weight. The means for removing the fibers is placed in advance of and under the control of, a sensitive detecting device adapted to detect variation in the web weight, so that if the web runs heavy a substantial amount of fibers will be removed by the trimming means, and if the web runs light, a smaller amount of fibers will be removed to thereby correct variations in weight and produce a uniform web.

Since the web leaving the carding machine may be too thick to be scanned satisfactorily by light

scanning mechanism, it is desirable to use some other type of scanning means. Experimental work done by others indicates that high frequency air waves or supersonic waves may be employed satisfactorily to scan a relatively thick mass or web of fibers.

Having in mind the foregoing the primary feature of the present invention resides in means located adjacent to the doffer cylinder of a carding machine and operable to remove varying small amounts of fibers from the carded web to thereby control the weight of the web that remains, and in means located along the path of travel of the web that has left the carding machine and adapted to detect variations in the web weight and also to vary the operation of the fiber removing means so as to produce a web of uniform weight per unit length.

A more specific feature of the present invention resides in an auxiliary doffer comb located near one end of the doffer cylinder and adapted to be moved a short distance length wise of the cylinder so as to trim more or less fibers from the carded web. The movement of this auxiliary doffer comb is controlled by scanning mechanism which is positioned to scan the trimmed web, and the fibers removed by this comb may be returned to the lap forming mechanism.

The scanning mechanism may consist of one or more wave transmitters disposed at one side of the plane of the advancing web and a corresponding number of receivers disposed at the other side of the plane of the web similar to the disposition of the light source and photo-electric cell disclosed in the above mentioned Lewis patent. A more simple form however resides in a transmitter disposed adjacent one edge of the traveling web and a receiver disposed adjacent the other edge of the web so that the high frequency air waves that scan the web will travel parallel to the plane of the web and edgewise therethrough.

The above and other features of the present invention will be more fully understood from the following description when read in connection with the accompanying drawings wherein:

Fig. 1 is a vertical sectional view showing the discharge end portion of a carding machine, the side frame of the machine near the observer being removed.

Fig. 2 is a sectional view taken on the line 2—2 of Fig. 1.

Fig. 3 is an enlarged view of the auxiliary doffer comb and associate parts as seen from the opposite side to that shown in Fig. 2.

Fig. 4 is a top plan view of a portion of the web which has been trimmed, and of mechanism for scanning the same;

Fig. 5 is a block and circuit diagram of the electrical connections for the scanning device and the motor controlled thereby; and

Fig. 6 is a sectional view showing a modified fiber trimming device.

The apparatus contemplated by the present invention for producing a carded web of highly uniform weight per unit length is designed to be applied to the ordinary commercial carding machine now in general use, and may be readily applied thereto without modifying the operation of the carding machine up to the point where the carded web is ready to be removed from the doffer cylinder. At this point it is proposed to trim or otherwise remove a small portion of the web depending upon the amount the web is overweight, so that after the web is trimmed it will have the desired uniform weight per unit length.

Various means may be employed for trimming or removing a portion of the web as it is ready to leave the doffer cylinder and one good practical means to this end resides in a short auxiliary doffer comb disposed adjacent one end of the doffer cylinder, and positioned below the usual doffer comb that extends entirely across the face of the doffer cylinder to strip the web from the rotating cylinder. This auxiliary doffer comb is mounted for limited sliding movement in the direction of its length so that when it is moved inwardly from one side of the machine it will trim a fiber strip from the web of a definite width, and as this auxiliary comb is moved in the opposite direction it will trim a narrower strip from the web, thereby controlling the weight of the portion of the web that remains. Another practical fiber trimming means resides in a traversing vacuum nozzle that may be substituted for the auxiliary doffer comb.

Since, as above stated, the carding machine may for the most part be of well known construction only so much of the carding machine has been shown in the drawings as appears to be necessary to make clear how the apparatus contemplated by the present invention is associated therewith:

The carding machine shown has the usual side frames 10 which are connected by transversely extending beams as usual. These side frames serve rotatably to support the usual card cylinder 11 mounted upon a central shaft, not shown, and this cylinder has a rigid cylindrical shell that is provided at each end with a supporting spider having the arms 12, and the outer surface of the cylinder 11 is covered with card clothing 13 as usual. This cylinder 11 rotates in the direction indicated by the arrow so as to carry downwardly towards the doffer cylinder 14 the carded fleece 15 of fibers which have been acted upon by the usual overhead flats, not shown. The doffer cylinder 14 is considerably smaller than the card cylinder and likewise has a rigid cylindrical shell which is supported by spiders provided at each end thereof and having the arms 16, and this cylinder 14 is supported and rotated by the central shaft 17. The surface of the cylinder 14 like that of the cylinder 11 is covered with card clothing 18 but the wires forming this card clothing are usually somewhat finer and more closely set than the wires forming the card clothing 13.

The surface speed of the card cylinder 11 is much faster than that of the differ cylinder 14,

and the direction of rotation of both cylinders is such, that as will be apparent from the arrows, the fleece 15 is carried downwardly by the rotation of the cylinder 11 into contact with the slower rotating card clothing of the cylinder 14. This serves to condense the fleece to form the web 19 and to transfer the fleece from the carding cylinder to the doffing cylinder as shown in Fig. 1. It is then carried downwardly about the lower side of the cylinder 14 and upwardly to the position where it is removed by the rapidly vibrating doffer comb 20 that constitutes a blade as long as the cylinder 14. This comb is vibrated rapidly close to the surface of the cylinder so as to strip the web 19 therefrom entirely across the carding machine as shown in Figs. 1 and 2. The comb 20 which may be of usual construction works in a well known manner and is connected by the supporting arms 21 to the shaft 22. This shaft is journaled near its opposite ends in the bearings 23. Vibratory movement is imparted to the shaft 22 by mechanism housed within the comb box 24 and which receives operating power from the belt driven pulley 25.

As the web 19 leaves the surface of the cylinder 14 it passes over a fixed web supporting bar 26 and then to the usual trumpet 27 through which it is drawn by the nip of the calender rolls 28 and 29, and it issues from the nip of these rolls in the form of a round fibrous mass or sliver 30 which passes to coiling mechanism and can, as usual. The calender rolls 28 and 29 and associated parts are supported by the frame 31.

The mechanism so far described by reference numerals is old and operates in a well known manner. The mechanism contemplated by the present invention to be associated with the ordinary carding machine so as to produce a more uniform web and sliver will now be described.

In carrying out the present invention it is contemplated that the carding machine will be operated to deliver a web which at all times will run somewhat overweight so that the desired weight of the web per unit length may be secured by continuously trimming from the advancing web just enough fibers to reduce the overweight web to the standard weight. This is accomplished in accordance with the embodiment of the invention illustrated in Figs. 1, 2 and 3 of the drawings by providing a short auxiliary doffer comb 32 which is supported for vibratory movement adjacent to the cylinder 14 by the arms 33 and hollow sleeve 34. This sleeve is mounted for longitudinal sliding movement upon the vibratory shaft 35 which extends into the comb box 36 having the operating pulley 37. This box vibrates its shaft similar to that of the box 24. The comb supporting sleeve 34 is keyed at 34^x to the shaft 35 so that the vibratory movement of the shaft 35 will be imparted to the comb 32 and this sleeve is slidably secured to the shaft 35 so that the comb 32 may be moved lengthwise of the surface of the cylinder 14 to trim a web strip 38 of different widths from the web 19 before the latter reaches the main doffer comb 20. The web strip 38 passes downwardly into a hopper 39 and the lower end of this hopper is preferably connected with exhaust means to thereby exert a downward pull on the strip 38 to facilitate the trimming of the same from the main web 19.

The means shown in the drawings for moving the auxiliary doffer comb 32 in the direction of its length so that it will trim a strip 38 of increased or decreased width from the web 19 comprises a reversing motor 40 having reducing gears

5

within the motor casing which are adapted to drive at a reduced speed a shaft extending laterally from the motor casing and which carries a gear 41. The teeth of this gear engage rack teeth 42 formed in one face of the sleeve 34. The arrangement is such that when the motor 40 rotates in one direction the sleeve 34 and comb 32 will be retracted to decrease the width of the strip 38 trimmed from the web 19, and when this motor is rotated in the opposite direction the comb 32 will be moved inward along the face of the cylinder 14 to trim a wider strip 38 from the web 19.

After the web 19 has been trimmed by the auxiliary comb 32 it passes upwardly to be removed from the cylinder 14 by the comb 20 as shown. The present invention contemplates that this trimmed web 19 upon leaving the cylinder 14 will be automatically scanned to determine whether or not it is of proper weight, and the present invention also contemplates electrical means whereby the reversing motor 40 is under the control of this scanning mechanism, so that if the scanned web is running light the auxiliary comb 32 will be shifted in one direction to trim a narrower strip 38 from the web 19 and thereby increase the web weight, and if the scanned web is running heavy the comb 32 will be shifted in the opposite direction to trim off more fibers and reduce the web weight.

The scanning mechanism shown in the drawing comprises a wave transmitter 43 mounted adjacent one edge of the advancing web 19, and a wave receiver 44 mounted adjacent the opposite edge of this web. These scanning elements 43, 44 are shown as supported by the brackets 45 mounted upon a transversely extending rail 46. The scanning device used preferably employs high frequency air waves or supersonic waves because of their ability to scan satisfactorily a thick mass of fibers so that the strength of the waves that reach the receiving element 44 will be inversely proportional to the weight of the web. The scanning waves sent out by the transmitter 43 travel approximately parallel to the plane of the web 19, and in order to keep this web within the narrow path traveled by the waves it is preferable to provide the guide rods 47 that prevent the fibers of the web from spreading laterally within the range of the scanning mechanism.

One form of electrical means for placing the reversing motor 40 under the control of the web scanning elements 43 and 44 will now be described, but it will be understood that the electronic means to this end may be varied extensively. Referring more particularly to Fig. 5, the wave transmitter 43 is or may be a conventional crystal transmitter of the quartz or Rochell variety, and having high frequency currents supplied thereto from a conventional electronic oscillator and amplifier 48. They are converted by the crystal to corresponding high frequency air waves or vibrations. The waves, in the construction shown as above stated, are directed against an edge of the traveling web 19 to penetrate therethrough and then impinge on a similar crystal receiver carried at 44. The resultant voltages generated in the crystal at 44 are transferred by shielded conductors to a conventional electronic amplifier 49 where they are reinforced or amplified prior to being used in the control circuits for the reversing motor 40.

Prior experiments show that when super sonic waves of a constant frequency and strength are transmitted from the crystal at 43, the voltages

6

they generate in the crystal at 44 and its amplifier 49 will be inversely proportional to the weight of the traveling web 19 being scanned. Hence, the output of the amplifier 49 is a usable signal or indicator of the weight of the scanned web.

In accordance with the present invention this weight signal is used as a means for controlling the direction of rotation and speed of the motor 40 to thereby control the amount of fibers removed from the web 19 by the auxiliary doffer comb 32.

The essential components of the control system illustrated in the drawing and their functions are as follows:

Tubes 50 and 51 are diode rectifiers of conventional construction connected to the output of amplifier 49 for the purpose of supplying a rectified signal to the grids of the tubes 52 and 53 respectively. It should be noted that the plate at 50 and the cathode at 51 are respectively connected to the output of the amplifier 49 so that a positive voltage above ground is obtained on resistor 54 and a negative voltage in respect to ground appears on resistor 55. These positive and negative voltages will always be equal and opposite and will vary simultaneously in proportion to the impressed signal voltage from the amplifier 49. The capacitors 56 and 57 serve the purpose of smoothing out the signal arriving at the grids of the tubes 52 and 53; i. e., removing some of the supersonic carrier component.

The tubes 52 and 53 are control tubes for supplying direct currents to the saturable core reactors, to be described, and which in turn control the alternating currents reaching the series type reversing motor 40 that controls the position of the side trimmer doffer 32.

Tubes 52 and 53 may be power amplifier tubes of either the triode or multigrid construction but for purposes of simplicity are shown as triodes with indirectly heated cathodes. It is desirable that the tubes selected should have definite plate current cut off characteristics for some reasonable negative grid bias voltage.

It should be particularly noted that the negative grid bias voltages for the tubes 52 and 53 are obtained on the voltage divider resistor 58 at the points 59 and 60 respectively.

With no signal voltage present on resistors 54 and 55, tube 52 should be biased to twice the plate current cutoff, while 53 should have a minimum bias to permit maximum plate current within the safe operating limits of the particular tubes selected.

Signal voltages appearing at resistors 54 and 55 (by adjustment of the output of amplifier 49) should be able, with a minimum absorption condition at the card web scanning point, to drive the grid of 52 in a positive direction to some predetermined maximum plate current, while 53 should be driven negatively past cut-off by an amount approximately equal to the positive increase in 52. In other words at this instant, 52 is conducting and 53 is not.

Since the signal voltages on 54 and 55 are added algebraically to the bias voltages of the respective tubes 52 and 53, a 50% maximum signal strength on 54 and 55 would cause both tubes 52 and 53 to be non-conducting. This method of biasing these tubes is essential to the operation of the saturable core reactors 61 and 62 as will be later explained. That is, the possibility of some simultaneous conduction in tubes 52 and 53 should be kept to a minimum by grid bias adjustment.

The saturable core reactors 61 and 62 may be

constructed in several different ways, but the one indicated (for reasons of simplicity) is built up of conventional shell type transformer laminations. In this construction the outside legs 63, 64, 65 and 66 respectively carry the alternating currents and the inside coils or middle legs 67 and 68 are direct current coils. The alternating current coils should be connected series aiding.

To fully understand the function of the reactors 61 and 62 it should be remembered that as the D. C. magnetization increases due to rising plate currents in the tubes 52 and 53, the alternating current impedances of the coils 63, 64, etc., decreases. By virtue of the mode of operation of the tubes 52 and 53 either one reactor or the other will be passing alternating currents through the motor 40 in proportion to its degree of D. C. magnetization. This then will determine the speed of the series wound motor. The particular reactor energized will determine the direction of rotation of this motor.

To trace the reactor circuit assume that reactor 61 and tube 52 are inactive, i. e., no plate current is flowing and that 67 is not energized. Hence, the A. C. impedance is maximum, and minimum alternating currents are flowing. Assume also that 53 is conducting and that 68 on reactor 62 is energized so that 62 may pass alternating currents. Then tracing from the 60 cycle supply at (1) the conducting path is consecutively through the motor field 69, coil 65 on reactor 62, the motor armature 70 from left to right, then through coil 66 or 62 and back to the supply at (2).

With reactor 61 active and 62 blocking, the path is consecutively from the 60 cycle supply at (1) through the motor field 69, coil 64 on reactor 61, the motor armature 70 from right to left, then through coil 63 on reactor 61 and back to the A. C. supply at (2).

The plate power supplied to the tubes 52 and 53 and other parts shown is indicated at B+.

From the above it will be observed that the direction of rotation of the motor 40 will depend on which reactor 61 or 62 is active, and the motor speed will depend on the degree of D. C. saturation.

Adjustment of the output of the amplifier 49 determines the "null" or non-operating position of the reversing motor 40, and its speed of response can be controlled by varying the plate current of the tubes 52 and 53 or by suitable taps on the coils 67 and 68.

Instead of employing the auxiliary doffer comb 32 shown in Figs. 1, 2 and 3 it may be desirable to employ a vacuum nozzle 71 having a long narrow suction slot 72. This suction nozzle 72 may be supported similarly to the comb 32 and is shown as secured to the sleeve 34 by arms 33. This sleeve is slidably mounted upon and is keyed to a shaft 35' which unlike the shaft 35 does not have to be vibrated. The sleeve 34 may be shifted back and forth along the fixed shaft 35' by the gear 41 and motor 40 the same as above described. The slot 72 should be about as long as the auxiliary comb 32, so that the width of the fiber strip 38' it removes from the web 19 will vary as this slot is moved lengthwise of the cylinder 14. To the lower end of the vacuum nozzle 71 is secured the large flexible tube 73 leading from suction producing means, not shown.

From the foregoing it will be understood that the carding machine operates as usual heretofore, except that it is supplied with a sufficiently heavy lap to produce a web that is slightly over-weight,

and that sufficient amounts of fiber are removed from the web adjacent the doffer cylinder to bring the weight of the web down to the desired uniform weight per unit length. The means shown in Figs. 5, 1, 2 and 3 for removing this small amount of fibers comprises an auxiliary doffer comb which is adapted to be moved in and out relative to a marginal edge portion of the web so as to trim more or less fibers from an edge of the web, and the means shown in Fig. 6 is a movable vacuum nozzle. This web is then scanned with supersonic waves capable of detecting variation in the density or weight of the traveling web and the scanning action of these waves is used to control the amount of fibers trimmed from the web to give the same the desired uniform weight.

Having thus described our invention, what we claim and desire to protect by Letters Patent is:

1. In combination with a carding machine for producing a carded web of fibers, mechanism for scanning a web traveling from the carding machine and adapted to detect variations in its weight, means adjacent the doffer cylinder of the carding machine for removing varying amounts of fibers from the carded web, and means under the control of the scanning mechanism and operable in response to the variations it detects to vary the action of said removing means to thereby control the web weight.

2. In combination with a carding machine for producing a carded web of fibers, mechanism for scanning a web traveling from the carding machine and adapted to detect variations in its weight, means adjacent the doffer cylinder of the carding machine for trimming varying amounts of fibers from an edge of the web, and means under the control of the scanning mechanism and operable in response to the variations it detects to vary the action of said trimming means to thereby control the web weight.

3. In combination with a carding machine having a doffer cylinder and a doffer comb for removing a carded web from said cylinder, mechanism for scanning the web as it travels from said cylinder and adapted to detect variations in its weight, an auxiliary doffer comb near one end of said cylinder and operable to trim varying amounts of fibers from an edge portion of said web, and means under the control of the scanning mechanism and operable in response to the variations it detects to shift said auxiliary comb and thereby control the web weight.

4. In combination with a carding machine for producing a carded web of fibers, mechanism for directing high frequency waves through a web traveling from the carding machine and adapted to detect variations in the web weight, means adjacent the doffer cylinder of the carding machine for removing varying amounts of fibers from the carded web, and means under the control of said mechanism for controlling the action of said fiber removing means to thereby control the web weight.

5. In combination with a carding machine for producing a carded web of fibers, mechanism for directing supersonic waves transversely through a web traveling from the carding machine and adapted to detect variations in the web weight, means adjacent the doffer cylinder of the carding machine for removing varying amounts of fibers from the carded web, and electroresponsive means under the control of said mechanism for controlling the action of the fiber removing means to thereby control the web weight.

6. In combination with a carding machine hav-

ing a doffer cylinder and a doffer comb for removing a carded web of fibers from said cylinder, mechanism for directing supersonic waves transversely through a web traveling from the carding machine and adapted to detect variations in the web weight, an auxiliary doffer comb operable to trim varying amounts of fibers from said web, and electro responsive means under the control of said mechanism and operable to shift the auxiliary comb to thereby control the web weight.

7. In combination with a carding machine for producing a carded web of cotton fibers, mechanism for scanning a web transversely as it travels from the carding machine and adapted to detect variations in the web weight by passing high frequency air waves therethrough, means adjacent the doffer cylinder of the carding machine for removing varying amounts of fibers from the carded web, and electroresponsive means under the control of said mechanism for controlling the action of said fiber removing means to thereby control the web weight.

8. In combination with a carding machine for producing a carded web of fiber, mechanism for directing supersonic waves edgewise through a web traveling from the carding machine and adapted to detect variations in the web weight, means adjacent the doffer cylinder of the carding machine for removing varying amounts of fibers from the carded web, and means under the control of said mechanism for controlling the action of the fiber removing means to thereby control the web weight.

9. In combination with a carding machine for producing a carded web of fibers, mechanism for

detecting variations in the weight of the carded web leaving the carding machine, means adjacent the doffer cylinder of the carding machine for removing varying amounts of fibers from the carded web, and means under the control of said mechanism for controlling the action of said fiber removing means to thereby control the web weight.

10. In combination with a carding machine for producing a carded web of fibers, mechanism for scanning a web traveling from the carding machine and adapted to detect variations in its weight, a vacuum nozzle adjacent the doffer cylinder of the carding machine for removing varying amounts of fibers from the carded web, and means under the control of the scanning mechanism and operable in response to the variations it detects to vary the amount of fibers removed by the vacuum nozzle to thereby control the web weight.
